UNITED STATES PATENT OFFICE.

OTTO SURKS, OF BROOKLYN, NEW YORK.

DESIGN FOR A TOY SAND PAIL OR SIMILAR ARTICLE.

Application filed July 16, 1925. Serial No. 14,116. Term of patent 7 years.

To all whom it may concern:

Be it known that I, OTTO SURKS, a citizen of the Republic of Hungary, residing at Brooklyn, in the county of Kings and State of New York, have invented a new, original, and ornamental Design for Toy Sand Pails or Similar Articles, of which the following is a specification, reference being had to the accompanying drawing, forming part thereof.

The figure is a perspective view of a toy sand pail or similar article, showing my new design, which latter comprises a form of pail and mold simulating the hull of a boat.

I claim:

The ornamental design for a toy sand pail or similar article, as shown.

OTTO SURKS.
